UNITED STATES PATENT OFFICE.

FRANK N. REEVES, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,235,599.

Specification of Letters Patent.

Patented Aug. 7, 1917.

Application filed November 14, 1916. Serial No. 131,230.

To all whom it may concern:

Be it known that I, FRANK N. REEVES, a citizen of the United States, residing at Newark, in the county of Essex and State of New Jersey, have invented certain new and useful Improvements in Telephone-Exchange Systems, of which the following is a full, clear, concise, and exact description.

This invention relates to telephone exchange systems, and more particularly to improvements in operators' listening key circuits.

In systems in which a multi-position switch is used to control the connection between the cord circuit with which said switch is associated and the operator's head set, a time interval has been necessary in order to allow such switch to move into its listening-in position in which the operator's head set is connected to the cord through contacts of the switch.

It is the object of the present invention to eliminate this time interval.

A feature of the present invention is the provision of a relay individual to each cord which will instantly connect the operator's head set to the desired cord upon depression of a listening-in key, additional contacts being provided on the multi-position switch to maintain the connection to the head set during a certain portion of the movement of such switch.

It is thought that the invention will best be understood from the following detailed description, reference being had to the accompanying drawing.

In the part of the drawing to the left of the dotted line is indicated a subscriber's substation apparatus, together with an operator's cord circuit and its accompanying apparatus. To the right of the dotted line are indicated portions of a second connecting cord. In the dotted rectangle at the bottom of the drawing is indicated a sequence switch associated with the first cord, while the dotted rectangle in the upper central portion of the drawing shows three relays common to all the cords of an operator's position.

The subscriber at substation 100 desiring a connection removes his receiver from the hook, causing the energization of line relay 101 and the resultant display of line signal 102 in the well-known manner. The operator, one of whose cords is indicated at O,

upon observing the lighting of signal 102, inserts a plug 103 into jack 104 associated with signal 102, whereupon cut-off relay 105 and relay 106 are energized, relay 105 removing the control of line relay 101 from the calling subscriber in the well-known manner. A circuit is now completed from grounded battery, winding of power magnet 107 of the listening key sequence switch, listening key sequence switch contact 108, armature and front contact of relay 106, to ground. The listening key sequence switch moves from position 1 to position 7 under the control of its normal contact 109. While the listening key sequence switch is moving from positions $1\frac{1}{4}$ to $6\frac{1}{4}$, the operator's head set 110 is connected to the desired cord circuit through listening key sequence switch contacts 111 and 112.

As soon as the listening key sequence switch arrives in position 2 a circuit is completed from grounded battery, winding of power magnet 113 of the district sequence switch, district sequence switch contact 114, listening key sequence switch contact 115, and the armature and front contact of relay 106, to ground. The district sequence switch moves from position 1 to position 2 under the control of its normal spring 116.

From position 1 to position 6 talking battery is fed to the calling subscriber from the repeating coil indicated at C, through listening key sequence switch contacts 117 and 118. When the listening key sequence switch arrives in position 7, conversation between the operator and the calling subscriber may continue, the operator's head set being connected through the armature and back contacts of common relay 119, the ringing keys indicated at K and listening key sequence switch contacts 120 and 121. At this time talking battery is fed to the calling subscriber through listening key sequence switch contacts 122 and 123, keys K and listening key sequence switch contacts 120 and 121.

Having ascertained the number of the wanted line, the operator depresses listening-out key LO and proceeds to set up the desired connection in the well-known manner. The depression of the listening-out key completes a circuit from grounded battery, winding of power magnet 107, listening key sequence switch contact 124, closed contact of key LO, to ground. The listening key se-

- quence switch thereupon moves out of position 7 and into position 11 under the control of its normal spring 109. If the operator does not depress the listening-out key, the 5 listening key sequence switch will be moved out of position 7 as soon as she responds to another call; for instance, if she responds to a call with the cord indicated at the right of the dotted line in the drawing. When the 10 sequence switch associated with such cord arrives in position 2, a circuit will be completed from grounded battery, winding of power magnet 107, listening key sequence switch contact 124, common conductor 125, 15 contact 226 of the listening key sequence switch associated with the second cord, to ground, whereupon the first listening key sequence switch will move to its listening-out position as before described.
- 20 If we assume now that the operator is listening in on the second cord whose sequence switch is therefore in position 7, and that she wishes to again listen in on the first cord whose listening key sequence switch is at 25 this time in position 11, she will depress listening-in key LI associated with said first cord, whereupon a circuit will be completed from ground, closed contacts of key LI, through relays 127 and 128 in parallel, listening key sequence switch contact 129, common relay 130, to grounded battery. Relays 127, 128 and 130 will be energized in this 30 circuit, relay 128 completing a locking circuit for these relays at its right-hand armature and front contact, ground now being supplied through district sequence switch contact 131 and the right-hand armature and front contact of relay 128, instead of through the listening-in key contacts. It 35 will be seen therefore, that the listening-in key need only be depressed momentarily.
- Relay 130, upon energization, completes a circuit from grounded battery, armature and front contact of relay 130, winding of relay 40 131, winding of relay 119, to ground. The operation of relay 119 opens the circuit from the operator's head set to the cord whose listening-in switch was in position 7, while relay 131 completes a circuit from ground 45 through its armature and front contact, listening key sequence switch contact 224, to the power magnet of the second listening key sequence switch for moving this switch out of position 7 and into position 11.
- 50 The operation of relay 127 instantly connects the operator's head set to the cord whose listening-in key has been depressed through the armature and front contacts of relay 127, while relay 128 completes a circuit 55 at its left-hand armature from grounded battery, winding of power magnet 107, listening-in sequence switch contact 132, the armature and front contact of relay 128, to ground, for moving this sequence switch out 60 of position 11 and into position 1.

The listening key sequence switch does not stop in position 1 since relay 106 is energized at this time, so that the circuit of power magnet 107 is maintained through listening key sequence switch contact 108 to ground 70 over the same path by which it was first moved out of its normal position.

When the listening key sequence switch moves out of position 2 contact 129 is opened, with the result that relays 127, 128 75 and 130 are deenergized. Relays 131 and 119 will remain energized until the listening key sequence switch leaves position 6, their energizing circuit extending from grounded battery, listening key sequence switch contact 133, winding of relay 131, winding of 80 relay 119 to ground.

While the listening key sequence switch is moving from position $1\frac{3}{4}$ to 6 $\frac{1}{4}$, the operator's head set is connected to the desired 85 cord circuit through sequence switch contacts 111 and 112 as previously described, and upon arriving in position 7, the listening key sequence switch connects the operator's head set to the cord through sequence switch contacts 120 and 121 and the back contacts of relay 119, as previously described.

It will therefore be seen that the operator is instantly connected to the desired 95 cord upon the depression of the listening-in key, and that this connection is maintained over alternate paths until the listening key sequence switch arrives in position 7 to establish the usual connection. Of the three 100 paths provided for connecting the head set to a cord, one is the usual path provided in the listening-in position of this sequence switch, while the other two auxiliary paths serve to maintain this connection while the 105 switch is passing from its normal to its listening-in position and from its listening-out position to its listening-in position, respectively.

What is claimed is:

1. In a telephone exchange system, a link 110 circuit, a multi-position switch associated with said circuit, an operator's telephone set, means including said switch to establish connection between said link circuit and said operator's telephone set, auxiliary means associated with said link circuit to establish temporary connection between said circuit and said operator's telephone set during movement of said switch means including 115 said switch to enable said operator to re-establish connection between said link circuit and said operator's telephone set, and means to operate said auxiliary means during the reconnecting movement of said 120 switch.

2. In a telephone exchange system, a plurality of subscribers' lines, a plurality of link circuits for interconnecting said lines, an operator's telephone set, a multi-position 130

- switch associated with each of said link circuits, means including said switch for connecting said operator's telephone set to a link circuit whenever a line is extended thereto, auxiliary means to establish temporary connection between said telephone set and said link circuit during the operation of said switch, a manually operable key associated with each of said link circuits, means responsive to a momentary depression of said key to instantly connect said operator's telephone set to the link circuit with which said key is associated if such circuit is then in use, and means actuated simultaneously with each new connection of said telephone set to disconnect said telephone set from the link circuit to which it was previously connected.
3. In a telephone exchange system, a plurality of subscribers' lines, an operator's position, a plurality of link circuits thereat for interconnecting said lines, an operator's telephone set, a multi-position switch associated with each of said link circuits, means including said switch for connecting said operator's telephone set to a link circuit whenever a line is extended thereto, a manually operable key associated with each of said link circuits, a relay individual to each of said link circuits responsive to a momentary depression of said key to connect said operator's telephone set to the link circuit with which said key is associated if such circuit is then in use, and a relay common to said link circuits actuated simultaneously with each new connection of said telephone, to disconnect said telephone set from the link circuit to which it was previously connected.
4. In a telephone exchange system, a plurality of subscribers' lines, a plurality of link circuits for interconnecting said lines, an operator's telephone set, three electrical paths over any one of which connection may be established between said telephone set and a desired link circuit, and means to close said paths at desired times.
5. In a telephone exchange system, a plurality of subscribers' lines, a plurality of link circuits for interconnecting said lines, a multi-position switch associated with each of said link circuits, an operator's telephone set, means for connecting said telephone set to one of said link circuits through contacts of said switch during a certain portion of the movement of said switch, a relay individual to each of said link circuits, means for establishing said connection through contacts of said relay, a relay common to said link circuits, and means for establishing said connection through other contacts of said switch in one of its resting positions and through contacts of said common relay.
6. In a telephone exchange system, a line, a link circuit, means for interconnecting said line and said circuit, a movable switch having a normal, a listening-in and a listening-out position, an operator's telephone set, means for associating said set with said line when said switch is in its listening-in position, and means for connecting said set to said line while said switch is moving from its listening-out to its normal position, and means for connecting said set to said line while said switch is moving from its normal to its listening-in position.

In witness whereof, I hereunto subscribe my name this 13th day of November A. D., 1916.

FRANK N. REEVES.
